[57] ABSTRACT

An edger mill velocity reference signal is developed as a function of the draft which occurs during the forward or odd pass through a reversing mill where the entry thickness of the material to be rolled is set during the reverse or even pass of the mill. The draft compensation necessary to adjust the edger drive speed is obtained, in the preferred embodiment, by computing the ratio of the reverse pass screwdown position to the following forward pass screwdown position.

FIG.1.

FIG.2.

FROM SEQUENCE CONTROL

AUTOMATIC DRAFT COMPENSATION FOR REVERSING MILL EDGER DRIVE

BACKGROUND OF THE INVENTION

In the process of rolling metal plate or other material several passes must be made through a main mill to reduce the height of the material and, at the same time, edge rolling may be required either to reduce the width or to hold a previously established width. This process may be carried out in a reversing horizontal mill where both edge and height rollings are performed during forward or odd passes, with the edge rollers preceding the horizontal or main mill rollers. The forward passes are sometimes referred to as odd passes since the first pass is forward and the second pass and even passes thereafter are in the reverse direction.

After each reverse or even pass, the edging mill speed must be adjusted for what has been referred to in the art as draft compensation due to the change in the material thickness as it passes through the mill in the forward direction. This change in thickness causes a corresponding change in plate speed. In existing reversing mill control systems, an operator periodically sets an initial edger speed rheostat to a nominal draft compensation setting. This setting provides a reasonably accurate draft compensation reference for some forward passes but it has been found that either forward or odd passes are then performed with errors existing in the draft compensation. The operator does not have time between passes to properly calculate and adjust the draft compensation reference signal to account for the change in edger velocity which should be made. As a result, there is a velocity mismatch between the edger mill drive speed and the main mill entrance speed with the result that the edger drive may attempt to push the product to the main mill or may attempt to pull the product from the main mill with the result that the edger motor current is either higher or lower than desired.

SUMMARY OF THE INVENTION

The edger drive speed reference is automatically adjusted during each forward pass to compensate for the draft which occurs during the forward pass. A system is provided where a representation of the mill delivery thickness (Hd) produced during an even pass becomes the edger entry thickness (He) for the next odd pass and the draft compensation then is automatically generated as the product of the mill delivery speed (Vd) times the ratio of Hd to He. This then provides an edger velocity reference signal which continuously varies to adjust the edger speed so that it is approximately equal to the main mill entry speed for the particular delivery speed occurring for a certain draft. The automatic control relationship satisfied by the invention may then be expressed as:

$$VE_{ref} = Vd * Hd/He.$$

In the preferred embodiment of the invention, a representation of height Hd is continuously developed by reading the screwdown setting of the main mill which differs from the desired height measurement only by mill stretch which is relatively small. The height or thickness representing signal then is stored in an analog memory (which could be a digital memory in an equivalent digital system) during each even pass and then is used as a representation of the entry thickness He dur-

ing the following odd pass to develop the ratio corresponding to Hd/He , where the Hd representation is continuously read during the forward pass to provide continuous draft compensation adjustment in the reference signal VE_{ref} during the forward pass. When the screwdown position representation is used as the approximation of height or thickness, the draft compensation ratio then becomes Sd/Se where Sd and Se correspond to Hd and He, respectively.

10 The above and other objects and features of the invention will become apparent from the following detailed description taken in connection with the accompanying drawings which form a part of this specification, and in which:

15 FIG. 1 shows a system employing an automatic draft compensator provided according to the invention; and

FIG. 2 is a schematic diagram of one form of automatic draft compensator as utilized in the system of FIG. 1.

20 Referring now to FIG. 1, it will be noted that a strip or plate 1 passes between edger rolls 2, only one of which is visible in FIG. 1, to main mill rolls 3. The edger exit velocity VE should be equal to the main mill entry velocity if proper draft compensation adjusts VE as will

25 be described in detail below. Edger rolls 2 are driven by a suitable drive 110 which receives a mixed reference signal VMref from a reference mixer 120 which receives the reference signal VE_{ref} provided by automatic draft-compensator 200. Compensator 200 functions on the basis of the delivery speed Vd provided by a transducer 130 which is suitably coupled to rolls 3 to

30 derive a representation of the circumferential velocity thereof. A representation of the delivery thickness or height Hd is derived through a screwdown position signal generator 140 which may form part of the screwdown control mechanism (not shown) associated with the main mill. Such apparatus is now well known in the art and, accordingly, is not shown or discussed herein. The representation of delivery thickness may be made

35 directly on the strip but in this case a separate measurement must be made to determine the entry thickness He as will be discussed below. A sequence control 150 is shown as providing a switching signal F/R which represents forward and reverse passes. Control 150 may form part of a computer system and may provide many other sequence control signals utilized throughout the entire milling process. Only signal F/R is of importance herein.

40 As shown in FIG. 2, compensator 200 receives screwdown signal Sd representing delivery thickness Hd during both forward and reverse passes. Signal Sd is applied both to a switch X1 shown in the open position and to a difference amplifier 210, the function of which will be explained below. The open position of switch X1 corresponds to the forward representation of the sequence control so that, during a forward pass, signal Sd is applied only to difference amplifier 210. During

45 a reverse pass, switch X1 is closed and analog memory 220 (which may be replaced with a suitable digital equivalent) stores a representation of Sd, during the reverse pass, on a capacitor C220. During forward passes switch X1 opens under control of signal F/R and analog memory 220 holds the previous screwdown position which then represents the entry height He for the next pass. Thus, during a forward pass, signal Sd represents the screwdown position during the forward pass which was applied to difference amplifier 210. The output of

analog memory 220 (referenced as Sm) provides the representation of the entry thickness He. It may be noted that the equivalent function of memory 220 would be to actually measure He during the forward pass but this would require additional hardware and, accordingly, the shared use of the screwdown representation Sd to provide both representations He and Hd is preferred in the practice of the invention. During a reverse pass when switch X1 is closed to develop a representation of height He, a second switch X2 is open and driver 230 receives a signal to reset a motorized potentiometer system including a motor 241, a first potentiometer 242, which receives the representation of He, and a second potentiometer 243 also driven by motor 241, which receives a suitable constant proportionality signal K. Potentiometers 242 and 243 will be referred to as the E and D potentiometers, respectively. Both potentiometers D and E are reset to an initial position by the reset signal during reverse passes so that at the beginning of a forward pass, potentiometer E receives the He representation and provides a tapped signal represented as $FE*He$ to signify that a signal derived thereof is the function of the position (FE) of potentiometer E and signal He applied thereto. It will be assumed in the following discussion that FE varies from 1 at the reset position to zero as potentiometer E is driven to the other extreme from the reset position. The output signal produced by difference amplifier 210 during a forward pass then may be represented as: $ER = Hd - FE*He$. During the forward pass, switch X2 is in the upper position shown and consequently driver 230 will move both potentiometers D and E from their initial reset position until signal ER becomes zero. When this occurs, the setting of potentiometer E may then be derived from the following:

$$ER = 0 = Hd - FE*He$$

$$FE*He = Hd$$

$$FE = Hd/He.$$

It may be seen, then, that the desired correction ratio is provided by the position of potentiometer E. However, the signal provided by potentiometer E after the error signal is zero must correspond to Hd and does not, therefore, provide the desired signal. Accordingly, potentiometer D is employed to develop a suitable representation of $K*Hd/He$ which is applied to an analog multiplier 250 also receiving signal Vd from transducer 130 of FIG. 1. It may be seen, then, that output signal $VEref$ produced by multiplier 250 may be defined as:

$$VEref = (K*Hd/He)Vd,$$

so that, during forward passes, the edger reference signal $VEref$ is continuously adjusted as a function of the delivery velocity Vd times the ratio of delivery thickness Hd to entry thickness He.

Reference is again made to FIG. 1 where it will be noted that reference mixer 120 may receive other control signals represented as manual control, roll diameter compensation, and a sequence control signal, not defined. The precise function of mixer 120 will not be considered herein since it does not form a part of the invention. Signal $VMref$, however, is developed as a function of $VEref$ during forward passes and that it is $VEref$ which provides the automatic draft compensation according to the invention.

It will be understood that while an analog system has been presented to illustrate one embodiment of the invention, the particular compensating relationships described herein may be developed by means of a digital computer. Other variations in the general technique taught by the invention for developing the compensating edger drive reference signal will be apparent to those skilled in the art.

We claim as our invention:

1. In a reversing mill wherein material to be rolled is moved forward during odd passes through edger rolls for width control and is moved in reverse during even passes without width control, an automatic draft compensating system comprising: first means for producing a first signal representing main mill delivery thickness during forward passes; second means for producing a second signal representing the delivery thickness of said main mill during even passes, said second signal then representing the entry thickness for the following odd passes; third means, operative during odd passes, for producing a draft correction signal proportional to the ratio of said first signal to said second signal; and fourth means responsive to a signal representing main mill delivery speed and to said draft correction signal for producing an edger velocity reference signal.
2. The automatic draft compensating system of claim 1 wherein said second means includes a memory operated during reverse passes to produce a signal representing the entry thickness for the next following forward pass.
3. The automatic draft compensating system of claim 2 wherein said memory is an analog memory including a capacitor for storing a signal representing said entry thickness.
4. The automatic draft compensating system of claim 1 wherein said first means produces a representation of delivery thickness during a forward pass as a function of the reversing mill screwdown position during a forward pass and said second means including a memory for producing a representation of the entry thickness of material as a function of the screwdown position during the reverse passes.
5. The automatic draft compensating system of claim 1 wherein said third means includes a difference amplifier for generating an error signal initially set to represent the difference between said first and second signals and further includes means for determining the fraction of said second signal that must be applied to said difference amplifier to reduce said error to zero.
6. In combination, an edger roller drive for establishing an edger velocity Ve, main mill speed transducing means for producing a representation of main mill delivery speed Vd and mill delivery thickness Hd, a sequence control for producing a signal F/R representing forward and reverse mill passes, and automatic draft compensation means responsive to signal Hd, F/R and Vd for producing an edger velocity reference signal $VEref$ for forward passes.
7. The combination of claim 6 wherein said automatic draft compensation means produces signal $VEref$ according to the function:

$$VEref = Vd*Hd/He,$$

where He is a signal representing entry thickness for a forward pass and Hd represents the forward pass delivery thickness.

8. The combination of claim 7 wherein signal He is produced by storing a signal representing Hd in a memory during a reverse pass.

9. The combination of claim 8 wherein signals Hd and He are represented by a screwdown position signal

5

Sd measured in the main mill, with the memory of the screwdown position signal produced during a reverse pass providing the representation of He for the following forward pass.
